DESIGN FOR AN EAR PROTECTOR

Cecile M. Sutton, Rochester, N. Y.

Application July 26, 1933, Serial No. 48,833

Term of patent 7 years

To all whom it may concern:

Be it known that I, CECILE M. SUTTON, a citizen of the United States, residing at Rochester, in the county of Monroe and State of New York, have invented a new, original, and ornamental Design for an Ear Protector, for use in tonsorial pursuits, of which the following is a specification, reference being had to the accompanying drawing, forming part thereof.

In the drawing:

Fig. 1 is an outer elevation of an ear protector, showing my new design;

Fig. 2 is an edge view taken from the open side, and

Fig. 3 is an inner elevation.

I claim:

The ornamental design for an ear protector, as shown.

CECILE M. SUTTON.
